BREAKING UP WATER AND OIL EMULSIONS

George L. Monighan, Oklahoma City, Okla.

No Drawing. Application July 26, 1938,
Serial No. 221,443

6 Claims. (Cl. 252—337)

My invention relates to means, including procedure and reactive material employed therein, for breaking up water and oil emulsions, particularly as issuing from the drill hole of a crude oil well, and an important object of my invention is to provide means of this character which are efficient, practical, labor-saving, and unusually economical.

Other important objects and advantages of the present invention will be apparent from a reading of the following description and examples therein given for illustrative purposes, and wherein I have set forth preferred embodiments of the present invention.

The employment of the procedure and reactive material of the present invention eliminates the provision and use of heaters, boilers, and gun barrels and the like, such as are usually necessitated in successful application of chemical reagents to the water in oil (petroleum) emulsion for breaking up the emulsion as it comes from the well-hole or flow line, and thereby much reduces the expense for equipment and the labor connected with operating the same, while providing better results. No heating is employed in conjunction with operating and utilizing the present invention.

In utilizing the present invention my reactive material is simply applied to the water in (crude) oil emulsion through the flow line or conduit direct to the stock tanks, where the water is caused to sink to the bottom of the tank and collect there after a few hours so as to be capable of being drawn off, whereby the water is substantially completely removed and that which remains in the tank is no longer an emulsion in the accepted sense. The complete reaction between the reagent and the emulsion whereby the desired results are obtained can take place at a temperature as low as 60° Fahrenheit, and even lower.

In actual practice of the invention I have successfully operated the present invention by subjecting the emulsion to a drag or blow through approximately one hundred and fifty feet or more of conduit from the head of the pumping well to the flow or stock tanks.

The reactive material of the present invention consists of the product of a mixture of substantially:

Per cent

Sulphonated castor oil or Turkey red oil	35.0
Rosin oil	36.8
Sodium hydroxide	1.2
Potassium hydroxide	1.4
Light wood oil, containing turpentine, rosin, creosote, and pine oil	25.6
	100.0

The foregoing ingredients are mixed in the

order in which they are set forth. The light wood oil referred to is known to the trade as such and is a distillation product of pine oil and contains turpentine, rosin, pine tar, creosote, and acids of value in this particular art.

I am aware that substantially all of the ingredients employed by me in obtaining my reactive material have heretofore been utilized in one form or another in products priorly as well as currently used for the same general purpose as that of the present invention. But I am unaware that there is among these prior or current products any combination, comparable to the present invention, which is a similar combination of sulphonated fatty ingredients and which will, under the same conditions, produce the results obtained by practice of the present invention, and without the use of gun barrels, heaters, or boilers. It will be recognized that these apparatus are in common use in oil fields all over the world.

While slight variations in the proportions of the ingredients such as might accidentally occur in handling do not seriously impair the usefulness and full effect of the reactive material of the present invention, it is to be understood that the full force and effect of the present invention cannot be obtained except by the compounding of the reactive material in substantially exactly the proportions set forth above.

Although I have set forth and described herein preferred embodiments of the procedure and material employed therein, of the present invention it is to be definitely understood that I do not desire to limit the application of the invention thereto, and any change or changes may be made in the materials and in the manner of compounding and employing the same, within the spirit of the invention and the scope of the subjoined claims.

Having described the invention, what is claimed as new is:

1. A method of demulsifying a water in crude oil emulsion, said method comprising subjecting the emulsion as it comes from the well at normal temperature to a demulsifying agent consisting of the product of a mixture of about 35% to Turkey red oil, about 36.8% of rosin oil, relatively small amounts of sodium hydroxide and potassium hydroxide, and about 25.6% of light wood oil, and allowing the resultant to stand, then removing the subsident water from the lower part of the resultant.

2. A demulsifier for use at normal temperatures for demulsifying a water in crude oil emulsion as it comes from the well-head, said emulsifier consisting of the product of a mixture of substantially 35% of Turkey red oil, 36.8% of rosin oil, 1.2% of sodium hydroxide, 1.4% of potassium hydroxide, and 25.6% of light wood oil.

3. The process of demulsifying a water and

crude oil emulsion which consists in subjecting the emulsion as it comes from the well at normal temperature to the resultant of a mixture of substantially 35% of Turkey red oil, 36.8% of rosin oil, 1.2% of sodium hydroxide, 1.4% of potassium hydroxide, and 25.6% of light wood oil.

4. The process of demulsifying a water and crude oil emulsion at temperatures in the neighborhood of 60° F. which consists in subjecting the emulsion as it comes from the well at normal temperature to the resultant of a mixture of substantially 35% of Turkey red oil, 36.8% of rosin oil, 1.2% of sodium hydroxide, 1.4% of potassium

hydroxide, and 25.6% of light wood oil, consisting of distilled pine oil.

5. A demulsifying agent of the character described containing substantially 1.2% of sodium hydroxide, 1.4% of potassium hydroxide, 35% of Turkey red oil, 36.8% of rosin oil, and 25.6% of light wood oil.

6. A demulsifying agent of the character described containing substantially 1.2% of sodium hydroxide, 1.4% of potassium hydroxide, 35% of Turkey red oil, 36.8% of rosin oil, and 25.6% of light wood oil, consisting of distilled pine oil.

GEORGE L. MONIGHAN.
